UNITED STATES PATENT OFFICE

EDWIN W. PIERSON, OF NEWARK, NEW JERSEY, AND FRED C. GRUMMAN, OF NORWALK, CONNECTICUT; SAID GRUMMAN ASSIGNOR TO MERGENTHALER LINOTYPE COMPANY, A CORPORATION OF NEW YORK

SLUG CASTING MACHINE

Application filed September 2, 1931. Serial No. 560,750.

This invention relates to slug casting machines, such as linotype machines of the general organization represented in U. S. Letters Patent to O. Mergenthaler No. 436,532, wherein a melting pot is arranged to deliver molten metal into a slotted mold and up against a composed line of matrices to produce a type bar or slug bearing on its edge type characters corresponding to the intaglio characters of the matrices. In these machines, the molds (usually four in number) are mounted in a rotatable wheel or disk which may be adjusted manually to bring any selected mold into use. During each cycle of operation, the active mold, by successive partial rotations of the disk, is first presented in a horizontal position for the casting of the slug and thereafter in a vertical position for the ejection of the cast slug. As the cast slug is ejected from the mold, it is pushed through or between a pair of fixed vertical trimming knives mounted in the machine frame and which act upon the opposite side faces of the slug to bring it to the exact thickness required.

The molds are secured in permanent positions on the rotatable wheel or disk with their respective slots or cavities spaced equidistantly from the axis of rotation, and the trimming knives are located in similar relation to said axis so as to stand in registry with the slot of the active mold at the time of ejection of the slugs, it being understood of course that the distance between the knives is adjusted to correspond with the width of the mold slot. The rotatable disk is usually formed with apertures or pockets wherein the molds are mounted, the lower or body portions of the molds being recessed or cut away in their rear side faces so as to fit within said pockets, and being provided with clamp screws which hold them firmly against the face of the disk.

Each mold is supported within its holding pocket by means of two contacting surfaces, one formed on the mold itself (the under face of the body portion), and the other formed on the lower or inner wall of the holding pocket. Great care and accuracy have to be observed in machining these surfaces, since

they alone determine the position of the mold on the carrying disk and the relation the mold bears to the slug trimming knives when the mold is in the slug ejecting position. In other words, unless said supporting surfaces are perfectly true and are properly spaced from the axis of the disk, the mold slot will in consequence stand out of line or parallelism with the knives at the time of ejection and the slugs will be unevenly trimmed.

In spite of the accuracy observed in manufacture, it occasionally happens that, because of the wear in the disk bearings, warping of the mold or the mold disk due to the alternate contraction and expansion of the parts, or for other reasons known to the art, the mold supporting surfaces in time lose their original shape or position relative to the axis of the mold disk and thus destroy the alignment of the molds with the trimming knives, resulting in imperfect slugs and entailing considerable time and labor in rectifying the trouble.

The present invention is intended to overcome these and other difficulties, and contemplates a simple expedient for positioning or repositioning the molds within the pockets without depending upon the accuracy of the mold supporting surfaces as heretofore necessary. To this end, the molds, instead of banking directly upon the pocket walls, are sustained by means of adjustable interponents arranged between said walls and the mold bodies. In the preferred embodiment illustrated, these interponents are in the form of partially rotatable pins mounted transversely in the molds at selected points in the length thereof, and having eccentric rearward extensions engaging the supporting wall of the pockets, whereby the rotary adjustment of the pins will tilt or move the molds bodily in relation to the pocket walls. The exact construction will best be understood from the detailed description to follow.

In the accompanying drawings, the invention has been shown merely in preferred form and by way of example, but obviously many changes and variations may be made therein and in its mode of application, which will still be comprised within its spirit. It should, therefore, be understood that the invention

is not limited to any specific form or embodiment, except in so far as such limitations are specified in the appended claims.

Referring to the drawings:

Fig. 1 is a front elevation of a so-called head-letter or recessed mold equipped with the present improvements;

Fig. 2 is a rear elevation thereof;

Fig. 3 is a vertical section taken on the line 3—3 of Fig. 1;

Fig. 4 is an enlarged detail, showing in full and dotted lines respectively different adjusted positions of the mold relative to the disk;

Fig. 5 is a horizontal section taken on the line 5—5 of Fig. 4; and

Fig. 6 is a vertical section of a regular unrecessed mold, showing the application of the present improvements thereto.

As shown in Figs. 1, 2 and 3, the mold A (of the recessed or "head-letter" variety) is mounted in the rotatable wheel or disk B, the latter being of standard construction and having a capacity of four molds, any one of which may be brought into use by a manual adjustment of the disk about its axis. Generally, the mold A comprises a body portion A¹, a cap portion A², and intermediate end liners A³, A⁴, these parts being held together in proper assembled relation by upright posts A⁵ rising from the body portion A¹ and engaging in open notches a (Fig. 5) formed in the opposite ends of the cap portion A². The disk B is provided as usual with apertures or so-called "pockets" B¹ wherein the molds are positioned, and which permit the selected mold, during casting, to be clamped directly between the mouthpiece of the metal pot at the rear and the composed matrix line at the front.

The mold holding pockets B¹ (see Figs. 1 and 2) are each defined by a lower horizontal wall B², two vertical side walls B³, and an upper wall B⁴, the latter wall being directly opposed to the lower wall and shaped to conform with the contour of the mold cap A². The lower or body portion A¹ of the mold A presents a plain or flat casting surface a¹, which forms one side wall of the mold slot, while the cap portion A² presents an uneven casting surface which forms the other side wall of the mold slot, being provided in its front face with a longitudinal groove a² and in its under face with a series of transverse grooves a³ and intermediate core sections or filling pieces a⁴. A slug cast in the mold A will, therefore, comprise a thin body portion, an overhanging face portion or shelf upon which the type characters are formed, and a series of transverse ribs projecting laterally from the body portion and giving support to the overhanging shelf. At the front, the body portion A¹ is provided with the customary aligning rib or lip A⁶ with which the lower projecting ears of the matrices en-

gage, and at the rear it is recessed or cut away so as to provide a longitudinal ledge A⁷ which has heretofore rested directly upon the lower wall B² of the mold holding pocket B¹.

When the mold A is mounted in its pocket B¹, it is customarily anchored in place against the face of the disk B by retaining screws A⁸, and ordinarily the lower surface a⁵ of the ledge A⁷ is made to fit accurately upon the upper finished surface b of the lower pocket wall B². As may be noted in Fig. 3, the wall B² is disposed directly below overhead binding screws B⁵ mounted in the upper wall B⁴ of the pocket B, and which, although intended primarily to clamp the cap portion A² down upon the liners A³, A⁴ act also to press the body portion A¹ or the mold as a whole down upon the pocket surface b.

However, as previously stated, the mold surfaces a⁵ and the pocket surfaces b, for one reason or another, eventually shrink or get out of true even if made accurate to start with, and in consequence the molds are caused to assume a false or improper position in their holding pockets B¹. The present invention overcomes this difficulty and provides means whereby the molds may be positioned within their holding pockets by an adjustable three-point support such that they can be set or forced (if necessary) into proper position on the disk B without regard to the accuracy of the mold surfaces a⁵ or the pocket surfaces b.

Such means, in the preferred embodiment illustrated, consists of three rotatable hardened steel pins mounted transversely in the body portion A¹ of the mold A, one D at each end of the mold and the other D¹ at the center. These pins are provided with screw heads D² accessible from the front of the mold to facilitate their rotation, and are formed with rearwardly extending eccentric portions D³ adapted to engage the banking surface b of the wall B² when the mold is positioned within its pocket B¹.

The pins D and D¹ are disposed in a horizontal line immediately below the matrix aligning rib A⁶ of the mold A, and to prevent interference between the center pin D¹ and the lower projecting ears of the matrices, the head of said pin is seated in a recess or counter-bore A⁹ formed in the front face of the body portion A¹ (see Figs. 1 and 3). The holes for the two end pins D are also counter-bored, as shown in Fig. 5, but such construction is not essential since these pins are located beyond the opposite ends of a matrix line of the maximum length.

To hold or lock the mold adjusting pins normally against rotation, set screws D⁴ of the ordinary kind, and which are arranged conveniently in notches A¹⁰ at the opposite ends of the mold body A¹, are provided for the end pins D, while a set screw D⁵ of a special design is provided for the center pin D¹.

This particular set screw D^5 is mounted in the mold body A^1 adjacent and parallel to the center pin D^1 and is formed with an enlarged head portion d , which engages a segmental flange d^1 integral with the screw head of the pin D^1 . The heads of both the pin D^1 and set screw D^5 , as well as the segmental flange d^1 , lie within the recess A^9 before referred to, and the latter is under-cut at d^2 to accommodate the flange d^1 and permit a full rotation of the pin D^1 . When the set screw D^5 is tightened up, its head d is adapted to clamp the flange d^1 securely against the vertical rear face of the recess A^9 and thus lock the pin D^1 against rotation. The other set screws D^4 function in a similar manner but they bind against the shanks of the pins D in the customary way.

As clearly shown in Fig. 3, the eccentric portions D^3 of the pins D and D^1 are substantially as long as the supporting surface b is wide, and hence they provide adequate and desirable means of support for the mold when it is positioned within its holding pocket B^1 . Moreover, (see Fig. 1), the supporting pins are vertically aligned with the three overhead screws B^5 , so that the pressure exerted by these screws individually will be transmitted directly to the disk B . It may be noted that the location of the pins D and D^1 relative to the supporting surface b is such that, in either the high or low position of the eccentric portions D^3 (see Fig. 4), the lower surface a^5 of the ledge A^7 of the mold will be sustained at a level above or out of contact with the surface b , the latter in the present instance thus acting to support the mold as usual but through the medium of the adjusting pins. Consequently, no special accuracy is required in machining the surfaces a^5 and b , particularly the latter (four of which have to be considered in finishing a disk of standard construction), representing a considerable saving in the cost of manufacture.

It will now be seen, according to the above arrangement, that when it is desired to position or reposition a mold in its pocket B^1 , the overhead binding screws B^5 in the periphery of the disk B , as well as the retaining screws A^8 in the front of the mold A , are first loosened to permit movement of the mold bodily toward or from the supporting surface b . In this connection, it will be understood (see Figs. 4 and 5) that sufficient clearance between the retaining screws A^8 and the walls of the screw holes is provided to allow such bodily movement of the mold A . The set screws D^4 and D^5 for the pins D and D^1 , respectively, are then turned to unlock said pins, and the latter with the aid of a screw driver may thereupon be adjusted to set the eccentric portions D^3 in whatever position or relation may be required. By this operation, the mold is raised or lowered, in angu-

lar or parallel relation to the supporting surface b , and after the proper position of the mold has been attained, the set screws D^4 and D^5 are tightened up to lock the adjusting pins D and D^1 against displacement. Finally, the mold is clamped in place by means of the overhead screws B^2 , which press the adjusting pins securely down upon the banking surface b , and by the screws A^8 , which anchor the mold facewise to the disk.

In the case of a warped mold, the adjustment of the pins D and D^1 may if required be resorted to only for straightening out the mold or bringing its slot back into parallelism with the trimming knives. Thus if the conditions demanded that the opposite ends of the mold be slightly depressed to straighten out a warped mold, the two end pins D could be turned to permit such depression, reliance being placed upon the opposed clamping screws B^5 to effect it.

It may here be stated that the eccentricity of the adjusting pins D and D^1 is intended merely to give a very small range of adjustment of the mold and in no case to be great enough to interfere with the ejection of the cast slug should the operator fail to make the proper mold adjustment. In other words the slug will always be able to pass through the trimming knives so that no danger can result from the most exaggerated mal-adjustment of the mold.

While the invention has been described above as applied to a "head-letter" mold, it is equally applicable to the regular or unrecessed type of mold E shown in Fig. 6. This type of mold, as is well-known, is designed to cooperate with matrix lines at two different levels, instead of one only as in the case of the "head-letter" mold A , and for such purpose the mold is ordinarily provided with two superposed matrix aligning ribs, the upper rib E^1 being located at the usual level adjacent the mold slot, and the lower rib E^2 (which is usually formed on a so-called "keeper plate" E^3 secured to the mold body) being located at a given distance below the rib E^1 . In adapting the present improvements to a mold so constructed, the keeper plate E^3 is provided with transverse apertures e, e^1 arranged one above the other below and rib E^2 so as to afford clearance for the head of the center pin D^1 and the tapered head of its associated set screw D^5 , respectively. The body of the mold E is formed with a recess c^2 corresponding to the recess A^9 in the mold A , but which in this instance is comparatively shallow and serves merely to permit free movement of the segmental flange d^1 of the pin D^1 . The mold E is sustained in precisely the same manner as the mold A by means of the eccentric portions D^3 of the pins D and D^1 and may be adjusted as and when desired by performing the same operations in the order before described.

It is recognized to be old broadly to mount a mold adjustably in its holding pocket, as for example as shown in the Pearce & Bilington Patent No. 1,220,782. The present arrangement however is far superior, since it presents advantages which the prior construction lacks entirely. For instance, one of the important features of this invention resides in the fact that the adjustable mold supporting means and the mold clamping means are arranged substantially in the same plane so that the clamping pressure and the resistance pressure are directly opposed. The advantage of such disposition of the parts will be derived whether the adjusting pins are supported on the lower wall of the mold holding pocket or not. The same is true so far as the location of the adjusting pins in line with the clamping screws is concerned. Again, another important feature of the invention is that the mold adjusting pins are carried by the mold, making a self-contained unit which can be applied to and removed from the machine as such. This same feature possesses added importance when the adjusting pins are arranged to bank upon the lower wall of the mold holding pocket, since in that way the improved mold may be applied to any of the outstanding linotype machines without change and used interchangeably with the standard molds now employed. Furthermore, the limited eccentricity of the mold adjusting pins is another feature of advantage, because it eliminates all possibility of injury to the parts due to carelessness or ignorance on the part of the operator. The advantages of the adjustable multi-point support of the mold have already been rather fully dealt with, but the feature is mentioned again lest its importance be overlooked or unduly minimized. These and other advantages will be readily apparent to those skilled in the art.

Having thus described our invention, what we claim is:

1. In a slug casting machine, the combination of a slotted mold, a carrier presenting a wall whereon the mold is supported, means for clamping the mold against said wall, and means, adjustable at will and while the mold is in place, arranged between the supporting wall and the mold for positioning the latter on the carrier and out of contact with the supporting wall.

2. In a slug casting machine, the combination of a slotted mold, a carrier formed with an aperture or pocket presenting a lower wall whereon the mold is supported and an upper wall directly opposed to the lower wall, means arranged between the upper wall and mold for clamping it against the lower wall, and means, adjustable at will and while the mold is in place, arranged between the lower supporting wall and the mold for position-

ing the latter within the pocket and out of contact with said supporting wall.

3. In a slug casting machine, the combination of a slotted mold, a carrier formed with an aperture or pocket presenting a lower wall whereon the mold is supported and an upper wall directly opposed to the lower wall, a plurality of binding screws mounted at selected points in the upper wall and acting to clamp the mold upon the lower wall, and a corresponding plurality of members mounted in the mold and engaging the lower wall of the pocket, said members being aligned with the respective binding screws and adjustable independently while the mold is in place to tilt or move the mold bodily in relation to the supporting wall to support the mold out of contact with said supporting wall.

4. In a slug casting machine, the combination of a slotted mold, a carrier formed with an aperture or pocket presenting a lower wall whereon the mold is supported and an upper wall directly opposed to the lower wall, a plurality of binding screws mounted at selected points in the upper wall and acting to clamp the mold upon the lower wall, and a corresponding plurality of pins rotatably mounted in the mold and formed with eccentric portions engaging the lower supporting wall of the pocket, said eccentric portions being vertically aligned with the respective binding screws and adapted by a partial rotation of the pins to tilt or move the mold bodily in relation to the supporting wall.

5. In a slug casting machine, the combination of a slotted mold, a rotatable disk formed with an aperture or pocket presenting a lower wall whereon the mold is supported and an upper wall directly opposed to the lower wall, means arranged between the upper wall and mold for clamping it against the lower wall, and a plurality of pins mounted transversely at definite points in the mold and formed with eccentric portions engaging the supporting wall of the pocket, said pins being capable of rotary adjustment and the eccentric portions thereof being adapted by an adjustment of the individual pins to locate the mold relative to the axis of the disk and to position it within the pocket.

6. In a slug casting machine, the combination of a slotted mold, a carrier formed with an aperture or pocket presenting a lower wall whereon the mold is supported, and means for adjusting the mold relatively to said wall including a plurality of rotatably adjustable pins mounted transversely in the mold and formed with eccentric portions engaging the supporting wall of the pocket, and set screws for locking the pins against rotation in their adjusted positions, one of said set screws being mounted in the mold parallel to the associated adjusting pin and formed with a head portion engaging a segmental flange.

or collar integral with said pin and banking against the face of the mold.

7. In a slug casting machine, the combination of a slotted mold, a rotatable disk provided with an aperture or pocket presenting a lower wall whereon the mold is supported and an upper wall directly opposed to the lower wall, screws located at definite points in the upper wall for clamping the mold down upon the lower wall, and rotatably adjustable pins formed with eccentric portions located directly below the respective screws and engaging the lower wall, said eccentric portions being adapted by an adjustment of the pins to locate the mold in relation to the axis of the disk and to position it properly within the pocket.

8. In a slug casting machine, the combination of a mold carrier, a slotted mold, and means for supporting the mold on the carrier at three separated points, said means comprising three independently adjustable members, one located at or near the center of the mold, and the other two at or near the opposite ends of the mold respectively.

9. A combination as specified in claim 4, characterized by the fact that the eccentricity of the mold adjusting pins therein referred to is such that the greatest adjustment of the mold by the pins will be insufficient to permit the ejection of a slug therefrom through the trimming knives with which the mold is intended to cooperate.

In testimony whereof, this specification has been duly signed by:

EDWIN W. PIERSON.
FRED C. GRUMMAN.
